[57] CLAIM

The ornamental design for a signal lamp for automobiles, as shown and described.

DESCRIPTION

FIG. 1 is a front elevational view of a signal lamp for automobiles showing our new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is an enlarged fragmentary top plan view of the portion of the lamp enclosed by lines 7—7 in FIG. 5;
FIG. 8 is a top front elevational view thereof; and
FIG. 9 is an enlarged cross-sectional view thereof as taken along the line 9—9 of FIG. 1.
